UNITED STATES PATENT OFFICE

FRANK SCHOUTEN, OF GLENARM, MARYLAND, ASSIGNOR TO THE BLACK & DECKER MANUFACTURING COMPANY, OF TOWSON, MARYLAND, A CORPORATION OF MARYLAND

BALANCED SPRING HAMMER MAGNETIC TYPE

Application filed February 7, 1931. Serial No. 514,178.

The invention relates to an electrically operated mechanical hammer of the magnetic type in which a solenoid or electromagnet, which may be of the standard conventional 5 design, operates a solenoid plunger or core which, instead of striking directly on the anvil, is connected to a ram by means of a spring or springs, preferably balanced springs, the natural period of vibration of the 10 springs and ram being in the preferred form of the invention an integral function of the period of reciprocation of the solenoid plunger, which is in turn determined by the frequency of the current in connection with 15 which the hammer is adapted to be used or the current changes applied to the solenoid and other conditions of operation.

Applicant's hammer, as constructed, may be treated as an example of the preferred 20 form of the invention. This hammer or type of hammer is adapted for use with a rectified current or other pulsating current having a frequency of 7200 pulsations per minute. With this current a speed of reciprocation is 25 imparted to the plunger which gives 3600 strokes a minute. The frequency of the current pulsations is, to a large degree, dependent upon the supply of current available, though this may be stepped up and down by 30 a well-known apparatus to give the desired frequency, and the frequency may further be changed by adjustment to accord with or vary from the natural period of vibration of the spring and ram, to vary the force of 35 the blow at the will of the operator.

In order to obtain the desired results, it is desirable that the movement of the solenoid plunger or core be stopped at certain definite points, and for this reason relief or stop 40 springs are located at each end of the path of the plunger to bring the plunger to a stop at each end of its stroke, the kinetic energy of the ram and springs being transferred to the bit or tool.

45 In the accompanying drawings I have illustrated a hammer of the solenoid balanced vibratory spring type in several different forms, showing various convenient applications of the principles of the invention to this type of tool.

In the drawings—

Figure 1 is a vertical longitudinal section on the axis of a hammer or reciprocating tool of this type embodying the invention, the same being broken away near the centre of 55 the barrel for convenience of illustration.

Figure 2 is a similar section of the lower end of the tool, this figure being continuous with Figure 1.

Figure 3 is a section on the line 3, 3 in 60 Figure 2.

Figure 4 is a complete longitudinal axial section of a modified form of the hammer in which substantially the entire reciprocating mechanism is mounted within the sole- 65

noid. Figure 5 is a view showing the ram, and a plunger or core in the form of a ring of magnetic material surrounding the ram, these parts being removed and separated from the 70 remainder of the construction, the ram having a spring casing formed integral with the ram.

Figure 6 is a transverse section on the line 6, 6 of Figure 4. 75

Figure 7 shows a somewhat different arrangement of the essential parts, the solenoid plunger in this instance being rigidly attached to the spring chamber of the ram which it encircles, being shown as located 80 near the centre.

Figure 8 is a transverse section on the line 8, 8 of Figure 7.

Figure 9 is a section through a spring casing and solenoid plunger or core, taken 85 on the axis of the latter, the ram being somewhat different from that of Figure 7; and

Figure 10 is a circuit diagram showing a convenient manner of connecting the solenoid coils to a pulsating current which is 90 preferably rectified for this purpose, whereby the circuit within the solenoid cores is subjected to the desired pulsations, in accordance with the well-known practice, giving a reciprocating action of the plunger or 95 core without necessity for any mechanical means for making and breaking the circuit.

Referring to the drawings by numerals, each of which is used to indicate the same or similar parts in the different figures, the 100

construction shown, particularly in Figures 1, 2 and 3, consists of two solenoid coils 1 and 2 of conventional design and arrangement, placed end to end, and enclosed within 5 in an outer shell or casing 3 known as the solenoid casing. In the preferred form of the invention shown, the solenoid coils 1 and 2 are wound about or otherwise enclose a guiding tube 4 of non-magnetic material, in 10 which the core or plunger 5 is slidably mounted.

This plunger is in turn secured to a piston rod 6 which extends downwardly through a suitable opening 7, into the spring casing 15 8 of the ram 9, being secured at its lower end to the balanced spring abutment 10 which is mounted in the casing 8 and freely movable therein, being supported between the balanced springs 11 and 12, which are 20 compressed between the centre abutment 10 and the ends of the casing at 14 and 15, hereinafter referred to as end abutments, the latter being thickened to serve as the striker end of the ram. The ram in turn 25 is mounted to reciprocate within a suitable hammer barrel 16, which is of suitable length and provided at its lower end with a tool bushing 17 for the tool or bit 18.

The solenoid casing 3 is shown as having 30 a threaded connection 19 with the hammer barrel 16, and the lower end of the solenoid casing is closed by means of a plate 20 which as shown is secured between the solenoid casing and the barrel and within 35 the upper enlarged end of the latter, being supported on a suitable shoulder 21 in the barrel just below the threaded portion 22.

The guiding tube 4, as shown, is closed at one end by the upper end of the solenoid 40 casing 3 and at the other end by the plate 20, and located within this tube at each end are stop springs 24 and 25, suitably secured, which contribute to the desired result by stopping the core 5 or arresting its motion 45 at definite predetermined points at the ends of its stroke when the kinetic energy of the ram and springs and the plunger 5 is transferred by the ram to the tool or bit 18.

In Figure 10 I have illustrated a circuit 50 diagram adapted to energize the solenoid in the construction, Figures 1, 2 and 3, or in any of the various constructions shown, though various different types of circuit may be utilized for this purpose to supply the 55 necessary current changes to the solenoid.

In accordance with the circuit diagram, Figure 10, the coils 1 and 2 of the solenoid are connected to a pulsating direct current which is ordinarily obtained by rectifying an 60 alternating current. In the preferred arrangement, the adjacent ends of the coils 1 and 2 are connected to a common return wire 27, and the ends of these coils 1 and 2, which are remote from the return connection 27, 65 are each connected as by wires 28 and 29

to the positive side of the line supplying the rectified or other pulsating current.

As already pointed out, a pulsating current thus supplied to the solenoid coils having 7200 pulsations a minute, causes 3600 70 strokes or reciprocations of the plunger 5 whereby the ram is vibrated at a corresponding speed, the number of strokes per minute being equal to the number of strokes of the core or any integral function thereof, depending upon the natural period of vibration of the springs and ram, as already 75 pointed out, and the frequency of the current, which may, if desired, be varied by suitable step-up apparatus 23, well known 80 in the art, which may be part of the electrical equipment of the plant in which the tool is operated.

As already pointed out, the stroke of the plunger 5, and hence of the spring abutment 85 or piston 10, is stopped or arrested at definite points by means of the relief or stop springs 24, 25, and the resulting reciprocation of the 90 solenoid plunger 5 timed with the pulsations or changes of the current, as already pointed out, is communicated through the reciprocating piston or spring abutment 10 through the balanced springs 12 and 11 to the ram 9, which is shown in this construction as integral with 95 the spring casing 8, the most efficient operation of the hammer, as already pointed out, being obtained when pulsations of the current and hence the strokes of the plunger 5 are equal to or an even function of the natural 100 period of vibration of the springs and ram.

Figures 4, 5 and 6 illustrate a modified and further developed arrangement of the mechanism, in which substantially the entire reciprocating mechanism, including the bulk of the ram and spring casing, which is auxiliary to the solenoid, is enclosed or encompassed within the solenoid. In this construction the solenoid core or plunger 30 is in the shape of a ring 105 of suitable magnetic material surrounding the spring casing 31 which is integral with and forms a portion of the ram 32 within which casing are mounted the balanced springs 33 and 34, being compressed between the ends 110 of the casing and a central abutment or piston 35. In the construction shown a pin 36 is passed through the piston or central abutment 35 and seated at its two ends in the plunger ring 30, the spring casing 31 of the ram being slotted longitudinally on both sides 115 at 37 to form ways for the pin providing for 120 and permitting the reciprocation of the same, and the hammer casing or barrel is enlarged centrally, forming an annular chamber 38 surrounding the central position of the ram or more particularly the spring casing 31 125 within which the solenoid coils 39 and 40, comprising the solenoid 41, are enclosed, the solenoid being provided, as in the previous instance, with a guiding tube 42 of non-magnetic material in which the solenoid plunger 130

or core 30 reciprocates, so that the tube 42 of non-magnetic material acts as a guide for the same. As in the previous instance, the guiding tube 42 contains stop springs 43 and 44 at 5 its respective ends, which serve to stop or arrest the plunger or magnet 30, and hence the abutment or piston 35 at certain definite points, determining with almost positive accuracy the stroke of the plunger and the piston or balanced spring abutment 35.

In the form of the invention shown, particularly in Figures 4 and 5, the ram 32, including the spring casing 31, is guided within a barrel 45, which is discontinued at the centre and separated into spaced sections 46 and 47, which are connected and supported at the centre and partially enclosed by the casing 38 already described, as containing the solenoid 41, comprising the coils 39 and 40. 20 The spacing of the barrel sections 46 and 47 provides a path for the solenoid plunger 30 which reciprocates between said sections 46 and 47 guided by tube 42. This spacing of the barrel sections also permits the solenoid 25 plunger to immediately overlie the spring casing which is integral with the ram and to which it is operatively connected by the abutment 35 and springs 33 and 34, the abutment 35 being carried directly on the plunger by 30 means of pin 36. The springs 33 and 34 in turn serve to transmit the motion of the spring abutment or piston 35 to the ram in the manner already described in connection with the construction of Figures 1, 2 and 3.

35 The important feature of the arrangement shown in Figures 4, 5 and 6, and described in connection therewith, is that it serves to shorten the hammer to a very considerable extent as compared to the construction of 40 Figures 1, 2 and 3, in which the barrel 16 is secured to the end of the solenoid casing 3, with the solenoid coils 1 and 2 therein, the reduction of the overall length being due to the inclusion of the spring casing 32, the 45 springs 33 and 34 and abutment 35 within the solenoid.

Figures 7, 8 and 9 show a different arrangement of the actuating parts of the tool, in which the operating parts are again enclosed within the solenoid core, producing a 50 shorter and more compact hammer as compared to the construction Figure 1, and more closely resembling the construction Figures 4, 5 and 6 except as to the specific arrangement of the core of the ram and of the balanced springs, as hereinafter more specifically described.

In this construction there is a tool casing 55 comprising a barrel 51 consisting of two sections 52 and 53 spaced in the direction of the stroke, whereby the spring casing 54 is guided in its reciprocating motion, and a central enlarged portion 55 containing and supporting the solenoid coils 56 and 57 in a position in which they surround the casing

54. This enlarged portion or coil casing 55 serves to support and connect the sections 52, 53 of the barrel 51, between which sections the solenoid plunger or core 58 is mounted to reciprocate in a guiding tube 59 of non-magnetic material within the solenoid coils. The movement of the plunger 58 is arrested at definite points at the ends of its stroke by stop springs 60 and 61, enclosed within the tube 59 and bearing against shoulders 62 formed on the inner ends of the barrel sections 52 and 53.

70 The solenoid core or plunger 58, in the form of a ring of magnetic material encircling the ram, is attached to the spring casing 54 in any suitable manner as by means of screw-threads 65 formed on the inside of the plunger ring and on the outside of the spring casing. The spring casing contains 75 balanced springs 66 and 67, and an abutment 80 or piston 68 supported between the balanced springs. In the form of the invention shown this piston or abutment is guided by means of a piston rod 69 extending through a suitable 85 guide bearing 70 in the upper end of the spring casing, the said upper end being shown in the form of a removable screw-plug 71. The ram 72, as shown, is secured to the piston or spring abutment 68, being 90 shown in Figure 7 as formed integrally with the piston rod 69, the integral structure 69, 72 being slightly enlarged and threaded at 95 73 just above the ram 72 which is of larger diameter than the piston rod 69 and engaged in a suitable threaded opening 74 in the 100 spring abutment or piston 68.

Figure 9 shows a slightly different alternative structure in which the spring abutment 76 is in the form of an annular shoulder formed at the centre of an integral ram 77 consisting of a guiding member or piston rod 78 which projects rearwardly or upwardly through the upper end of the spring casing 79 in which it has a suitable guide bearing 81', and a striker member 80 which projects through the opposite end of the spring casing 79 and in which it has a guide bearing at 82'. The spring casing is shown as formed in two similar sections 81 and 82 connected together by threading their open ends into the corresponding threaded plunger ring 83. Balanced springs 84 and 85 bear at their outer ends against the corresponding ends of the casing 79, and at their inner ends against the spring abutment shoulder or collar 76.

110 In both instances, i.e., constructions of Figures 7 and 9, the ram member reciprocates through and relatively to the spring casing, being controlled in its relation thereto by the balanced springs 66 and 67 in one instance, and 84 and 85 in the other instance, and by the pulsations of the current in the solenoid and the corresponding reciprocations of the solenoid plunger, the natural 115 120 125 130

period of vibration of the springs and ram in each instance being preferably an integral function of the current pulsations, and hence of the speed and period of reciprocation of the plunger whereby the speed and period of reciprocation of the ram is determined and the most efficient operation of the hammer results.

I have thus described specifically and in detail the various embodiments of the solenoid type of balanced spring hammer embodying the features of my invention in order that the manner of constructing the same, and applying, operating and using the invention may be clearly understood. However, the specific terms herein are used descriptively rather than in a limiting sense, the scope of the invention being defined in the claims.

What I claim as new and desire to secure by Letters Patent is:

1. The combination in a portable power-driven hammer of a solenoid, having a core, means for energizing the solenoid periodical-
ly to reciprocate the core, a ram, means for
guiding the ram, and balanced spring means
connecting the ram to the core whereby the
reciprocating motion of the core is imparted
by the spring to the ram.

2. The combination in a portable power-
driven hammer of a solenoid having a core,
means for energizing the solenoid periodical-
ly to reciprocate the core, a ram, means for
guiding the ram in a path parallel to the path
of the core, balanced springs connecting the
ram to the core whereby the reciprocating
motion of the core is imparted to the ram with
a frequency which is a function of the fre-
quency of the reciprocations of the core and
the natural frequency of vibration of the
spring and ram, and stop springs for control-
ling the stroke of the solenoid core at each
end.

3. The combination in a portable power-
driven hammer of a solenoid, a core for the
solenoid, means for energizing the solenoid
periodically, and producing current changes
therein to reciprocate the core, a ram, and
means for communicating the reciprocations
of the core to said ram, including opposed
balanced springs.

4. The combination in a portable power-
driven hammer of a solenoid and core, means for
energizing the solenoid and producing peri-
odic current changes therein to vibrate the
core, balanced springs and a spring abutment
rigidly connected to the core for communicat-
ing the vibrations of the core to the springs,
and a ram to which the vibrations of the core
are communicated through and by way of the
balanced springs.

5. The combination in a portable power-
driven hammer of a solenoid and a core, means for
energizing the solenoid and producing peri-
odic current changes therein to vibrate the
core, balanced springs and a spring abutment

rigidly connected to the core for communicat-
ing the vibrations of the core to the springs,
and a ram to which the vibrations of the core
are communicated through and by way of
the balanced springs, and resilient means for
limiting and determining the stroke of the
core.

6. The combination in a portable power-
driven hammer of a solenoid, means for en-
ergizing the same producing periodic current
changes therein, a core co-operating with the
solenoid and reciprocated by and in response
to said current changes, a spring casing se-
cured to the core, said casing being provided
with spaced abutments and balanced springs
compressed between the abutments, a piston
between said springs, and a ram operated by
said piston through and by way of the bal-
anced springs.

7. The combination in a portable power-
driven hammer of a solenoid, means for en-
ergizing the same producing periodic current
changes therein, a core cooperating with the
solenoid and reciprocated by and in response
to said current changes, a spring casing en-
circled by and secured to the core, said cas-
ing being provided with spaced abutments
and balanced springs compressed between the
abutments, a piston between said springs and
a ram operated by said piston through and
by way of the balanced springs, and resilient
means for limiting the stroke of the core.

8. A combination in a portable power-
driven hammer of a solenoid, a core, means
for energizing the solenoid, and producing
periodic changes therein to reciprocate the
core, a spring casing secured to the core and
enclosed within the solenoid, opposed bal-
anced spring means therein, a spring abut-
ment supported by the spring means, and a
ram rigidly connected to said abutment to be
operated by and through said spring means
from said core.

9. The combination in a portable power-
driven hammer of a solenoid, a core, means
for energizing the solenoid and producing
current fluctuations therein to reciprocate the
core, a spring casing and balanced springs
therein enclosed within the solenoid and in-
cluding a ram connected to the casing, and
a spring abutment between said springs rig-
idly connected to the core for communicat-
ing the vibrations of the core through said
springs and to said ram.

10. The combination in a portable power-
driven hammer of a solenoid and core, a non-
conducting tubular guide for the core within
the solenoid, means for energizing the
solenoid, and producing current changes
therein to reciprocate the core, spring stops
at each end of the tube to limit the motion
of the core, a spring casing, and balanced
spring means therein having an abutment
at each end and an abutment supported in-
termittently of said spring means, part of

said abutments being secured to said core, and a ram to which the remainder of said abutments is secured, the ram being likewise enclosed within the solenoid whereby the motion of the core is communicated by and through the springs to the ram.

11. The combination in a portable power-driven tool of a solenoid, a core for the solenoid in the form of a ring, means for producing periodic current changes in the solenoid to reciprocate the core, a spring casing encircled by the core and secured therein, balanced springs inside the casing and a spring abutment between the springs which are compressed within the casing, and a ram secured to said spring abutment to be operated thereby and also enclosed within the solenoid.

12. The combination in a portable power-driven tool of a solenoid having a core, means for energizing the solenoid and producing periodic current changes therein to reciprocate the core, a spring abutment secured to the core, a ram having spaced spring abutments, and spring means compressed between said spring abutments, the spring abutment carried by the core being supported intermediately of said spring means whereby the motion of the core is communicated to the ram through said spring means.

13. The combination in a portable power-driven tool of a solenoid having a core in the form of a ring, means for energizing the solenoid and producing periodic current changes therein to reciprocate the core, a spring abutment secured to the core, a ram having spaced spring abutments and enclosed spring means compressed between said spring abutments, the spring abutment carried by the core being supported intermediately of said spring means, whereby the motion of the core is communicated to the ram through said spring means, the natural period of vibration of the spring means and ram being an integral function of the speed of vibration of the core and the period of current change.

14. The combination in a portable power-driven tool of a solenoid having a core in the form of a ring, means for energizing the solenoid and producing periodic current changes therein to reciprocate the core, a spring abutment secured to the core, a ram having spaced spring abutments and enclosed springs compressed between said spring abutments and encircled by the core and by the solenoid, the spring abutment carried by the core being supported between said springs whereby the motion of the core is communicated to the ram through said springs.

Signed by me at Towson, Baltimore County, Maryland, this 4th day of February, 1931,
FRANK SCHOUTEN.
